[57] **CLAIM**

The design for a headgear mountable light, as shown and described.

DESCRIPTION

FIG. 1 is a perspective view of a headgear mountable light showing my design with the cord broken away to indicate indeterminate length;

FIG. 2 is a front elevational view thereof;

FIG. 3 is a side elevational view, the other side being a mirror image thereof;

FIG. 4 is a rear elevational view;

FIG. 5 is a top plan view thereof; and,

FIG. 6 is a bottom plan view thereof.
